MOBILE HOME DECORATIVE MOLDING

Robert S. Wormser, Hillsdale, Mich., assignor to Game Time, Inc., Litchfield, Mich.

Filed Mar. 19, 1970, Ser. No. 21,982

Term of patent 14 years

Int. Cl. D25—01

U.S. Cl. D13—6

FIG. 1

FIG. 2

FIG. 1 is a plan view of a decorative molding element constructed in accord with my new design particularly suitable as a corner molding for mobile homes and travel trailers, as taken from the left of FIG. 4,

FIG. 2 is a side elevational view of the molding, as taken from either the top or the bottom of FIG. 4,

FIG. 3 is a view taken from the opposite side of that illustrated in FIG. 1, as from the right of FIG. 4, and

FIG. 4 is an elevational sectional view of decorative molding constructed in accord with my design as taken along section IV—IV of FIG. 1, the plastic inserts illustrated may have an outer surface of a solid color, or represent a wood grain.

I claim:

The ornamental design for mobile home decorative molding, substantially as shown and described.
